UNITED STATES PATENT OFFICE.

ALBERT H. PETTIT, OF NEW ORLEANS, LOUISIANA.

FRAME FOR BICYCLES.

SPECIFICATION forming part of Letters Patent No. 595,459, dated December 14, 1897.

Application filed December 26, 1896. Serial No. 617,070. (No model.)

To all whom it may concern:

Be it known that I, ALBERT H. PETTIT, of New Orleans, in the parish of Orleans and State of Louisiana, have invented certain new and useful Improvements in Frames for Bicycles; and I do hereby declare that the following is a full, clear, and exact description thereof, reference being had to the accompanying drawings, and to the letters of reference marked thereon, which form a part of this specification.

This invention relates to improvements in frames for bicycles, and has for its object the construction of the frame which will provide a spring action or vertical movement of the horizontal member of the frame to produce an easy riding of the bicycle, while at the same time avoiding any variation of the distance between the seat and the pedals. This object is accomplished by extending the bottom fork of the frame, to which the rear wheel is secured, beyond or in rear of said wheel and by uniting the outer ends of said fork to the upper member of the frame, preferably to the upper end of the seat-post member, by a horizontal connection of wood or spring metal.

The invention will be more fully understood by reference to the accompanying drawings and to the claim appended to this specification.

In said drawings, Figure 1 represents in side elevation the rear end of a bicycle-frame constructed in accordance with my invention. Fig. 2 is a horizontal sectional view taken on the line 2 2 of Fig. 1, looking in the direction indicated by the arrows. Fig. 3 is a top plan view of the same.

Referring to the drawings, A represents the upper horizontal member of a bicycle-frame of any approved construction, and B the seat-post member of such a frame, at the lower end of which is mounted the usual crank-axle hanger B'. C C are the bottom-fork members, suitably secured in a familiar manner at their forward ends to extending thimbles b b upon the hanger B'. At the usual distance from the crank-hanger B', and what would in the ordinary construction be the rear end of said fork members C C of the frame, I place a slotted bearing-bracket C' to ac-

commodate the rear axle of the wheel, which latter is indicated by dotted lines C². This bearing-bracket C' may be secured to the fork member C in any convenient manner. In 55 lieu of the usual construction in bicycle-frames—namely, the placing of the forks to extend between the wheel-bearings at the outer end of the bottom-fork member C and the upper end of the seat-post member, as in 60 diamond frames—I extend the two fork members C C rearwardly to a point beyond the wheel C², as more clearly shown in Fig. 1, and connect the outer end c of the said fork members C C with the upper end of the member B of the frame by a curved resilient member D. This connection may be made in any suitable manner, but I have shown for the purpose of illustration merely an angle-iron d and bolts and nuts d' d², and as shown in 65 Fig. 2 the angle-iron d is preferably made of such width as to extend across the space between the ends c c and thus act as a tie-plate to keep the ends c c from spreading, while at the same time firmly uniting the ends c c 70 to the resilient bar members D D. As a further means of strengthening the frame I sometimes use a tie bolt or rod E. This rod E, which is shown as formed by a single piece bent upon itself to stand with its two members in parallel relation, is secured at its lower end to the fork members C C by inserting 75 its ends through the said fork members adjacent to the point of attachment of the bearing-brackets of the rear axle, and said ends are held in position by nuts e, secured on the screw-threaded ends of said rod E. The upper portion of the rod E stands at right angles to the parallel side members thereof and is pivotally secured against the under 80 side of each of said resilient members D D by means of a bracket E', secured by screws e' or otherwise, the middle or right-angled portion of said rod E being shown more clearly at e² in Fig. 3.

As shown in the drawings, the resilient members D D of the frame are made of wood, and in practice I find that this construction gives the very best results; but I do not desire to be limited thereto, since it will be perfectly 85 obvious that resilient metal, such as spring-steel, may be also used. Neither do I desire to 90

be limited to the details of construction shown, as they may be varied without departure from the spirit of the invention.

What I claim, and desire to secure by Letters Patent, is as follows:

In a bicycle-frame, the combination with the bottom-fork members thereof, said fork members being extended rearwardly beyond the rear-wheel axle and the seat-post member, of a resilient spring removably mounted in said frame and secured at one end to the rear ends of said bottom members and at its opposite end to the upper end of said seat-post member and a brace extending between

said bottom-fork members and spring, said 15 brace being made of a single rod attached at its opposite ends to said fork members and engaging between its ends a bracket secured to said spring.

In testimony that I claim the foregoing as my invention I affix my signature, in presence of two witnesses, this 25th day of September, A. D. 1896.

ALBERT H. PETTIT.

Witnesses:

P. H. PRIEUR,

A. H. BROWNE.
